HYDRAULIC SYSTEM COMPRISING A SERVOMOTOR OF THE FOLLOW-VALVE TYPE AND IMPROVED CONTROL MEANS THEREFOR

Edward M. May, Detroit, Mich., assignor to Meco-Pilot Manufacturing Company, Detroit, Mich., a corporation of Michigan

Application December 3, 1949, Serial No. 131,025

5 Claims. (Cl. 121—45)

1

This invention relates to improvements in hydraulic drive and control systems of a type in which a movable machine element is moved and controlled by a hydraulic motor having a follow-valve for control of the admission and exhaust of the motor working fluid and in which the follow-valve of the motor is actuated by a hydraulic transmitter and continuously controlled in its position by the position of the transmitter piston or plunger.

A hydraulic system of the character specified is shown in my copending application Serial No. 719,305, filed December 30, 1946, now abandoned, which may be referred to for a detailed disclosure. The apparatus as there disclosed is employed to drive respective elements of a turret lathe and the hydraulic parts of the system comprise a plurality of reciprocating motors of the follow-valve type each operatively connected to a lathe element, means for supplying pressure fluid to the motors, and means for actuating the follow-valve of each motor comprising a piston connected to the valve element and exposed to hydraulic pressure in a receiver chamber, a plurality of hydraulic transmitters of which each has its fluid chamber connected by conduit to the receiver chamber of one of the follow-valves, and actuating cams for the transmitters mounted on a rotatably supported motor-driven cylinder or carrier. In the operation of such a system the hydraulic motor pistons are subject to the continuous positional control of the transmitter pistons and their positions in turn are determined by the form of their actuating cams.

It is an object of the present invention to provide a hydraulic system of the type above described in which the movements of the machine element determined by the follow-valve are caused to conform to predetermined dimensions more accurately than can be obtained from the hydraulic transmitter alone.

It is also an object of the invention to provide a hydraulic system of the specified type in which the follow-valve movements can be made to depart, in a predetermined manner, from the control of the transmitter in accordance with operating conditions affecting the follow-valve motor of the element driven by it.

Additional objects of the invention, more or less ancillary, incidental or supplemental to those stated above, will be apparent from the disclosure which follows.

In accordance with the invention the stated objects, and others ancillary or incidental to those referred to above, are attained by providing

2

in association with the follow-valve and its motor mechanical means which cooperate with the follow-valve to supplement the control thereof by the transmitter in a predetermined manner. Such supplementary control means may take a variety of forms such, for example, as a template device of one form or another, stop devices, and so on, the supplementary means serving by positive engagement with the follow-valve, or part connected thereto, to determine the position of the movable element of the follow-valve motor with a high degree of accuracy.

By way of further explanation of the invention and ways in which it can be practiced reference is had to the accompanying drawings showing exemplary embodiments and to the detailed description thereof which follows, the nature and scope of the invention being particularly pointed out in the appended claims.

20 In the drawings,

Fig. 1 is a plan view, largely diagrammatic, showing a portion of a turning lathe and hydraulic apparatus embodying the invention and arranged to drive and control the cutting tool of the lathe.

25 Fig. 2 is a vertical sectional view of a drilling or tapping apparatus having hydraulic driving and controlling apparatus presenting another embodiment of the invention, some features of the hydraulic apparatus being shown diagrammatically.

30 Fig. 3 is a vertical sectional view of a drilling or tapping apparatus of the type shown in Fig. 2 but having a modified form of control means.

35 Fig. 4 is a transverse section on the line 4—4 of Fig. 2 showing main parts of the apparatus in rear elevation.

40 Fig. 5 is a transverse section on the line 5—5 of Fig. 3 showing some parts of the apparatus in rear elevation.

45 Referring in detail to the constructions shown in the drawings and first to that shown in Fig. 1, numeral 1 designates the main frame of a turning lathe which supports live spindle 2, carrying work-holding chuck 3, and the usual tail stock 4. A carriage 5, slidably mounted on the frame, in turn carries a cross-slide 6 on which is mounted a conventional compound slide 6a carrying a cutting tool 7 arranged to engage the work piece 50 W. Compound slide 6a is aligned parallel to cross-slide 6 for manual adjustment of tool 7 to cut a work piece to desired diameter.

The carriage 5 is moved by a hydraulic motor, designated generally by the numeral 8, which is rigidly bolted to the carriage. Motor 8 is of the

follow-valve type and comprises a cylinder 9 in which is mounted piston 10 having its rod 11 anchored as shown to the frame structure. Motor 8 is controlled by follow-valve 12 of conventional type. The valve is biased towards the right by spring 13 and is fitted at its right end with a piston 14 exposed to the pressure in a hydraulic receiver chamber 15. A follow-rod 16 rigidly connected to piston rod 11 extends into receiver chamber 15 to function in well known manner as a movable displacement plunger or element. Motor 8 is supplied with pressure fluid under control of valve 12 by means of conduit 17 which may be connected to a suitable source such as a motor driven pump (not shown), and exhaust conduits 18 and 19 lead from the valve chamber to exhaust, which may be the sump of the supply pump.

The valve 12 is fitted with a stop rod 20 which extends through the end of the valve casing and is arranged to cooperate, in a manner which will later be explained, with one or the other of the stops 21 and 22 which are supported by trough-shaped bracket 23 from main frame 1.

The cross-slide 6 is actuated by means of a hydraulic motor 24 which, except for dimensional differences, is of the same construction as motor 8. The power elements of motor 24 are cylinder body 25, which is rigidly bolted to the cross-slide, and piston 26 which has its rod 27 anchored to the carriage 5. The follow-valve 28 is biased by spring 29 and is fitted with piston 30 which is open to the pressure of hydraulic receiver chamber 31 into which extends follow-rod 32 which is rigidly supported from piston rod 27. Conduit 33, which may be connected to the same pump which supplies conduit 17, affords a source of working fluid under pressure and exhaust passages 34, 35 may lead to the sump of the same pump.

Valve 28 is fitted with a stop rod 36 which is arranged to cooperate with a template 37 mounted on a rigid frame 38 secured by bolts 39, 39 to main frame 1.

The hydraulic motors 8 and 24 are controlled primarily by hydraulic transmitter mechanism which is generally designated by numeral 40 and is of the same type as that disclosed in my previously mentioned application Serial No. 719,305. While the transmitter mechanism may be embodied as a part of a lathe or other machine tool, it will be assumed that it constitutes a separate unit, as in the case of the construction shown in application Serial No. 719,305.

The transmitter mechanism comprises two hydraulic transmitters generally designated 41 and 42. These transmitters and other parts of the transmitter mechanism will be understood to have suitable support, which may be afforded by a unitary frame structure. Each of the transmitters 41 and 42 comprises a hydraulic cylinder part 43 in which is mounted a piston or plunger 44 that is biased by spring 45 toward the right. Each cylinder 43 communicates with a gravity feed replenishment reservoir (not shown) through aperture shown by dotted lines at 43a. The cylinder of transmitter 41 communicates through a conduit 46 with the receiver chamber 15 associated with the motor 8 of the lathe, while the cylinder of transmitter 42 communicates through conduit 47 with the receiver chamber 31 associated with motor 24.

The pistons 44 of the transmitters 41 and 42 are actuated by cams 48 and 49, respectively. These cams are in the form of sheet metal strips

and have their cam surfaces formed on the left longitudinal edges of the strips, as shown in the drawing. The cam strips are formed of suitable metal, such as aluminum, and are sufficiently flexible to be bent into circular form and secured, as by screws (not shown) on the surface of a cylinder 50 that may be understood to be rotatably mounted on the supporting frame of the transmitter mechanism and driven by an electric motor (not shown). In the drawing the two cam strips are shown in developed form to facilitate explanation of their construction and operation.

To effect the movements of the transmitter pistons 44 against the tension of springs 45 cam followers are provided in the form of lever arms 51, 52. These arms carry anti-friction rollers 53 to engage the active surfaces of the cams and are pivotally mounted on the heads of bolts 54, 54 slidably mounted in the blocks of cylinders 43. Bolts 54 are biased towards the left by coil springs 55 which normally hold the heads of the bolts yieldingly in contact with the adjacent surfaces of the cylinder blocks. Arms 51, 52 operatively engage the rods or stems of pistons 44 so that movement of the arms toward the left advances pistons 44 against the tension of springs 45.

An end-wise-slidable and spring-biased rod 56 is mounted adjacent the transmitters and carries contact fingers 57 in position to be engaged by the heads of bolts 54 if the bolts are moved towards the right against the tension of springs 55. An electric switch 58 in a circuit that supplies current to the motor that rotates the cylinder 50 is arranged adjacent the end of rod 56 so that movement of the rod toward the right will actuate the switch to open the said circuit.

From the foregoing description it will be apparent that motor 24 and its various adjuncts, other than stop rod 36 and the associated transmitter 42, constitute essentially a conventional follow-valve motor designed for hydraulic transmitter-receiver actuation of the valve; and a corresponding statement is applicable to motor 8 and its adjuncts other than stop rod 20 and transmitter 41. Thus in the case of motor 24, for example, the automatic follow-valve action is due to follow-rod 32. Assuming the position of cross-slide 6 is such that stop rod 36 is not in contact with template 37 and valve 28 is free to slide in its bore, when movement of transmitter piston 44 forces liquid into receiver chamber 31 the pressure on valve piston 30 moves valve 28 upward (on the sheet) to admit working fluid to cylinder 25 above fixed piston 26 so that the cylinder is moved upward relative to the piston, carrying with it the cross-slide 6 and tool 7. This causes a similar movement of receiver chamber 31 relative to fixed follow-rod 32 and enlarges the capacity of the chamber. As long as the transmitter piston movement continues to supply liquid to receiver chamber 31 equal in amount to the enlargement of the chamber, valve 28 remains in open position and the motor movement continues. But when transmitter piston 24 stops, the spring-biased valve 28 moves to closed (neutral) position and the motor movement stops. The amounts of the motor and transmitter linear movements are different but proportional, in the ratio of the cross-sectional area of the transmitter piston to that of the follow-rod. The displacement effect of the follow-rod, varying directly with the motor movement, is the essential function of the said

rod. However, it may (as indicated in Figs. 2 and 3) be made of a suitable length to engage the valve structure and actuate the valve in a manner to terminate the return movement of the motor.

In explaining the operation of the entire apparatus, it will be assumed that a finishing cut is to be made on work piece W, the cams 48 and 49 of the transmitter mechanism and the template 37 of the lathe having been designed for this purpose. In Fig. 1 the parts of the apparatus are shown in the positions occupied at an intermediate stage of such an operation. Starting with the roughed-out work piece mounted in the lathe, the carriage 5 in a starting position with valve stop rod 36 opposite the right end of template 37 and cam cylinder 50 positioned with the upper ends of the cams engaging the rollers 58, cam 49 will first swing transmitter arm 52 to the left to exert pressure in receiver chamber 31 of motor 24 and advance stop rod 36 to the right corner of template 37. However, cam 49 is made a slight amount higher than is needed to just cause contact of stop rod 36 with the template. This excess height of the cam is marked "S" on the drawing. The excess height of the cam causes compression of spring 55 by an amount marked "T" and puts a corresponding tension on the hydraulic transmitter-receiver system somewhat in excess of that necessary to move the follow-valve into contact with the template, so that positive engagement between the valve structure and template is insured notwithstanding inaccuracies in the hydraulic transmitter-receiver system. The excess height "S" of the cam is made reasonably constant over the form needed to generate the template shape so that the spring compression "T" stays constant and the transmitter-receiver system pressure stays constant. This contributes to the accuracy of the apparatus since variation of the contact pressure on the template will cause material departure from the true positioning of the follow-valve which is sought.

Beginning at line A cam 48 starts to rise and feed the carriage 5 to the left. Valve stop rod 36 now follows template 37 over the double curved form and carries tool 7 with it. At line B cam 49 falls away while cam 48 continues to feed carriage 5 to the left until valve contact rod 29 strokes stop 21 to position the carriage exactly in line with the slot in template 37. Cam 48 rises more than enough to contact stop 21 by the amount "U" which tensions the hydraulic system of transmitter 41 in the manner previously described.

Beginning at line C, cam 49 feeds the tool 7 straight into the work until stop rod 36 strikes the bottom of the slot in the template 37. This accurately establishes the diameter at the bottom of the groove in the work. The excess cam height "S" is used at this point also and a short dwell insures that the tool will finish its cut. Cam 49 then recedes, causing withdrawal of tool 7. At line D cam 48 drops back to remove tension between valve stop rod 20 and stop 21. At this point the operator should remove stop 21 from its holder 23. However, if stop 21 is not so removed the mechanism is automatically protected against injury; for if cam 48 continues to revolve while carriage 5 is unable to travel, due to its valve being held closed, spring 55 associated with bolt 54 will be deflected until the bolt head strikes finger 57 to open switch 58 75

and stop the cam cylinder until the operator puts things in order.

From line E to line F the second half of the curved form of the template is traced in the same manner as the first half. Here stop rod 20 strikes the stop 22 and is put under tension by cam 48 while cam 49 feeds tool 7 outward to face shoulder W1 on the work at an accurate distance from the middle groove of the work piece, this distance being determined by the length of stop 21. At line G cam 48 drops away to feed carriage 5 back to its starting position.

Before the low parts of cams 48 and 49 are reached, follow rod 32 strikes valve 28 thereby pushing it to neutral position and stopping servomotor 24. At this stage the cams have extra throw, or, more accurately speaking, negative throw, shown at "Y." This allows the transmitter cylinders to be relieved to reservoir pressure without any strain or heavy stress at the servomotors such as occurs when a mechanical back stop is used to directly limit the motor movement. Furthermore the follow-valves respond instantly when their transmitters are sealed (by the passing of apertures 43a) on their next forward strokes because the valves are already at neutral position instead of being in wide open reverse position. This saves part of the transmitter stroke and gives a more accurate starting position for the servo-motor.

In the improved apparatus the follow-valve, under the alternate control of the hydraulic transmitter and positive stop or control means, is very sensitive. Thus under conditions of low friction and light tool cuts the tool 7 can be controlled to within 0.0005 inch of the correct relation to the template 37. This discrepancy represents the valve travel required to reverse the valve and cause follow motion of the motor piston in the reverse direction. If no reversal is involved, as where the hydraulic transmitter is operated repeatedly to stop movement of the motor in the same direction, the discrepancy between successive stops of the motor may be no more than plus or minus 0.0001 inch. These figures are to be compared with errors in the system employing control by the transmitter system alone which are in the order of 0.005 inch, or approximately ten times as great as for the present system of control. With regard to the high degree of accuracy attained by the present system, it will of course be understood that its attainment requires the usual nice adjustment of the width of the follow-valve lands to the ports with which they cooperate. This may be secured either by making the width of the valve lands equal to or slightly less than the port widths or the valve lands may be made wider than the ports and accurately notched at their corners, both expedients being well known in the art.

Figs. 2 and 4 of the drawing represent an embodiment of the invention in drilling or tapping mechanism suitable for use in a machine tool of the type in which a plurality of tools are supported radially around a central turret which is indexed periodically to present a work piece to the several tools in succession. In Fig. 2, 61 is a portion of the flat annular top of the machine frame, 62 is a portion of a central frame block on which a turret, partially shown at 63, is mounted for rotation about a vertical axis. A fixture partially shown at 64 carries a work piece W2.

The drilling mechanism comprises a base 65 which is secured by bolts to the frame part 61,

said base being formed at its front or inner end with an upstanding guide section 65a. The main body 66 of the drill mechanism has a dove-tail sliding connection with base 65 (Fig. 4) and set screw 67 serves to secure body 66 in adjusted position on the base.

Body 66 is formed with a cylinder bore 68 to receive piston 69 carried by tubular rod 70 which projects from the inner and outer ends of the cylinder bore. Body 66 is also formed with bore 71 to receive follow-valve 72 which cooperates with an inlet port 73 and exhaust ports 74 and 75 to control flow of the working fluid to and from cylinder bore 68 through ducts 76 and 77. Valve 72 is biased toward the right by spring 78 and is fitted with a piston 79 which is exposed to the pressure in bore 71 a portion of which serves as a receiver chamber 80. The latter chamber communicates through a conduit 81 with a hydraulic transmitter generally designated by 82 and comprising a cylinder element 83 and piston 84. A cam diagrammatically indicated at 85 is of the same type as that disclosed in Fig. 1 and may be considered to be similarly mounted and actuated. This cam actuates piston 84 through a follower arm 86 pivoted to the end of bolt 87 which is slidably supported subject to the pressure of spring 88. The piston rod 79 is provided at its inner end with cross-head 89 to which is adjustably secured a follow-rod 90 that extends into receiver chamber 80 so that the valve 72, under actuation by transmitter 82, is caused to function as a follow-valve.

A drill spindle 91 disposed in the hollow piston rod 70 is rotatably supported at its inner end in ball bearing 92 and is fitted with a chuck 93 which may carry a tapping tool or, as shown in the drawing, a drill 94. At its other end drill spindle 91 has a spline connection with and is supported by a rotatable element of hydraulic motor 95, the said motor being mounted on a cross-head 96 which is in turn rigidly attached to the outer end of piston rod 70.

Control of the follow-valve 72 by the combined action of spring 78 and transmitter 82 is supplemented by mechanical stop means comprising a pin 97 rigidly connected to the valve, a plate-shaped lever 98, supporting means for said lever, and adjustable stop rod 99 carried by cross-head 96. The plate 98 is retained in upright position by screws 100 and 101 which extend through vertically elongated slots in the plate and are attached to body 66. Sleeve 102 on screw 101 serves as a fulcrum abutment for the lower end of the plate. The plate is formed with laterally extending lugs 98a which rest upon supporting rods 103 carried by cross-head 96 and having sliding engagement at their front or inner ends with apertures in the main body 66. Rods 103 serve both to sustain the reaction of rotary motor 95 and to support plate 98. In normal operation of the apparatus plate 98 is sustained at the elevation shown in the drawings and when the motor piston is fed forward the stop rod 99 will engage the plate and cause it to contact pin 97 and move the valve 72 to its neutral or closed position to stop the advance of the drill.

In addition to the normal stop action last described above, provision is made for emergency stopping, as follows. Body 66 is bored to receive a tubular slide 104 which is held against rotation by pin 105. A spring 106 is arranged to resist rearward movement of the slide 104. Threaded rod 107 is adjustably mounted in slide 104 with its front end slidably supported in lug 75 to receive piston 118 which is carried by tubu-

65a on base 65. Near its outer end slide 104 is formed at its upper side with a notch 108 which is directly beneath the lower end of lever 98 when the tool is in the retracted position shown in the drawings. The plate-supporting rods 103, 103 also are formed on their top sides with notches 103a which, when the tool is retracted, are out of line with the plate 98, as shown in Fig. 2.

In the operation of the drill the front or inner end of the rod 107 is designed to operate as a probe in cooperation with a recess 63a formed in the face of the turret 63, the arrangement being such that the recess 63a is in accurate alignment with the rod 107 when the turret has been properly indexed to bring the work piece W² into correct alignment with the drill. When the tool is in the retracted position shown in Fig. 2 the lower end of cross-head 89 holds the slide 104 in the position shown with spring 106 under some tension. Hence when the tool moves forward from its retracted position the said spring causes rod 107 to move toward the turret. If the recess 63a of the turret is aligned with rod 107 slide 104 will move forward far enough to carry its notch 108 out of alignment with the bottom of lever 98 and during the continued feeding movement of the tool the slide 104 will prevent the plate 98 from moving downward. If recess 63a is not in alignment with the probe 107 the latter will engage the face of the turret 63 and prevent more than a slight forward movement of slide 104. Then with continued forward movement of the motor piston, the supporting rods 103 will be advanced to bring their notches 103a under lugs 98a of the lever 98 thus interlocking the rods with the lever so that the upper end of the latter is moved forward to engage pin 97 and close valve 72. The feeding movement of the machine is thus stopped and engagement of the cutting tool with a wrong part of the work piece, or with the fixture in which the work piece is supported, is prevented.

To permit use of the rod 107 for adjustment of the motor body 66 toward and away from the turret, a latch 109 is pivotally mounted on the rear end of base 65 in position to swing up into interlocking engagement with rod 107 so as to prevent the rod from endwise movement. With the motor piston retracted (valve 72 closed) and set screws 67 loosened, the body of the motor can then be adjusted forward or backward by rotating rod 107. Screws 67 are then tightened and latch 109 disengaged from rod 107.

The apparatus shown in Figs. 3 and 5 of the drawing presents an application of the present invention in which the combined motor control by the hydraulic transmitter and the automatic mechanical stop means is adapted to compensate for incorrect setting of the work piece in order to maintain uniformity of repetitive work performed, for example, the depth of a drilled hole.

In this last apparatus the machine illustrated is of the same turret type as that shown in Figs. 2 and 4 and comprises top frame plate 111, a central block 112 sustaining turret 113, to which is attached a fixture 114 to hold the work piece W³. As in the construction already described, the hydraulic motor comprises a body 115 adjustably mounted on base 116 which is bolted to the frame part 111. The base 116 is fitted with a threaded rod 117 which engages body 115 to effect adjustment of the latter relative to turret 113.

The body 115 is formed with a cylinder bore 118 to receive piston 119 which is carried by tubu-

lar rod 120, the piston rod being provided at its front end with a cross-head 121. The body 115 is also bored to receive follow-valve 122 which is biased toward the right by spring 123 and is fitted with a piston 124 which is exposed to pressure in receiver-chamber 125. Conduit 126 connects the receiver chamber with a cam actuated transmitter similar to that shown in Fig. 2. Follow-rod 128 carried by cross-head 121 enters receiver-chamber 125. The valve and actuating transmitter are of substantially the same construction as that shown in Figs. 2 and 4 and the motor body 115 is formed with passages to supply and exhaust working fluid to and from the motor cylinder under control of the valve in the same manner as in Figs. 2 and 4.

A drill spindle 129 rotatably mounted in piston rod 120 carries chuck 130 and drill 131. A cross-head 132 is rigidly attached to the rear-end of piston rod 120 and in turn carries rotary hydraulic motor 133 which rotates spindle 129. Cross-head pins 134 carried by cross-head 132 take the reaction of motor 133.

The mechanical control means to supplement the valve control by the hydraulic transmitter comprises a pin 135 which is rigidly attached to the follow-valve, a plate-shaped lever 136 which is loosely supported from body 115 by screw 137 and stop pin 138 adjustably mounted in cross-head 132. The mechanism further comprises a second plate-shaped lever 139 which is formed with a vertical slot to receive a shouldered fulcrum screw 140 and the shouldered end of a stop rod 141 which is slidably mounted in body 115 and supports lever 139. A cross-head 142 adjustably mounted on the threaded front end of stop rod 141 carries a torque rod 143 which slidably engages an aperture in the lower end of the cross-head 121. A coil spring 144 is mounted on the stop rod between cross-heads 121 and 142, the reaction of the spring being taken by pin 145 in rod 141. The cross-head 142 carries a contact plate 146 designed to engage the work piece W³.

In the operation of the last described apparatus, when the drill spindle 129 advances toward the work piece its movement is transmitted through spring 144 to the contact plate 146 and the latter is advanced with the spindle until its front end touches the work piece W³ as shown by dotted lines in Fig. 3. This advance of the stop rod 141 moves lever 139 to a vertical position indicated by dotted lines in Fig. 3 and permits the upper lever 136 also to move forward to its dotted line position. Thereafter, as the drill spindle continues to advance, spring 144 is compressed by reason of the engagement of contact plate 146 with the work piece. Finally the stop pin 138 contacts the upper lever 136 and causes it to move the valve 122 to neutral or closed position, stopping the drill. The levers 136 and 139 are designed so that their arms, measured from their lower pivotal ends, are in the ratio of 1:2. Hence, in the operation just described, if the work piece W³ should be clamped in its fixture farther from the retracted position of the drill than it should be, there will be a correspondingly longer travel of the spindle before contact plate 146 engages the work and an exactly similar increase in the travel of stop pin 138 before it engages lever 136 with the result that the hole drilled in the work will be of the true predetermined depth X. Similarly if the work is clamped too close to the retracted position of the drill, a less than normal forward feed of the

drill spindle will bring about contact of plate 146 with the work piece and stop pin 138 will actuate the follow-valve at a correspondingly earlier point in the travel of the spindle, and again the hole drilled will be of proper depth.

From the foregoing description it will be apparent that the present improvements serve to notably extend the usefulness of the apparatus disclosed in the application Serial No. 719,305 in fields of work demanding a quite high degree of accuracy of servo-motor operation. Furthermore the present system makes possible the accurate stopping of a powerful servo-motor without subjecting the parts of the apparatus to any greater stress than is involved in the working stroke of the motor, whereas the application of a positive stop directly to the motor involves a stress equal to the maximum capacity of the motor. The latter practice calls for heavy machine parts and larger costs both direct and incidental.

It will be apparent from the nature of the exemplary embodiments of the invention herein disclosed that the invention is applicable in a wide variety of structural forms and for many different purposes. The appended claims are intended to be read, accordingly, as covering a wide range of embodiments within their bounds.

What is claimed is:

1. The combination of a hydraulic servo-motor having a follow-valve; means for supplying pressure fluid to the motor under control of its follow-valve; and means for actuating the follow-valve comprising a hydraulic transmitter, mechanical means for operating the transmitter, a hydraulic receiver having a piston arranged to move the follow-valve, conduit means and a body of liquid therein operatively interposed between the transmitter and the receiver to transfer transmitter movement to the receiver and its piston and thereby apply moving force to the follow-valve, an element of the means for applying the said moving force to the valve being constructed to yield under predetermined stress, and unyielding mechanical means arranged for engagement with the valve structure and operable when so engaged to apply to the valve a moving force induced by movement of one of the two power elements of the motor in opposition to the force of the hydraulic transmitter.
2. Hydraulic apparatus as claimed in claim 1 in which the follow-valve motor has its piston element fixed against axial movement and its cylinder element supported for such movement.
3. Hydraulic apparatus as claimed in claim 2, in which the unyielding mechanical means for applying moving force to the follow-valve comprises a template arranged for relatively movable engagement with the follow-valve structure and in which the cylinder element of the follow-valve motor is mounted for movement transversely of the motor axis to provide lateral movement of the follow-valve structure relative to the template while the former is maintained in contact with the latter by the pressure of the hydraulic transmitter.
4. Hydraulic apparatus as claimed in claim 1 in which the mechanical means for actuating the hydraulic transmitter comprises a motor-driven cam, in which the train of pressure-transmitting means between such cam and the follow-valve comprises a movable means constructed to yield under a force somewhat in excess of that required to overcome the resistance to movement of the follow-valve, and in which the cam is

11

shaped to establish such a force when the follow-valve structure is in operative engagement with its unyielding mechanical actuating means and to establish a corresponding force between the follow-valve structure and said unyielding mechanical actuating means.

5. Hydraulic apparatus as claimed in claim 1 in which the mechanical means for actuating the hydraulic transmitter comprises a motor-driven cam, and in which the train of pressure-transmitting means between such cam and the follow-valve comprises a movable means constructed to yield under a force somewhat in excess of that required to overcome the resistance to movement of the follow-valve.

EDWARD M. MAY.
